(57) **CLAIM**

The ornamental design for an electric cooker, as shown and described.

DESCRIPTION

Figure 1.1 illustrates a perspective view of an electric cooker of the present invention;

Figure 1.2 illustrates a front view of the electric cooker shown in Figure 1.1;

Figure 1.3 illustrates a rear view of the electric cooker shown in Figure 1.1;

Figure 1.4 illustrates a left side view of the electric cooker shown in Figure 1.1;

(Continued)

Figure 1.5 illustrates a right side view of the electric cooker shown in Figure 1.1;

Figure 1.6 illustrates a top view of the electric cooker shown in Figure 1.1; and,

Figure 1.7 illustrates a bottom view of the electric cooker shown in Figure 1.1.

Figures 1.1 through 1.7 illustrate an electric cooker. Broken lines, illustrated in various views, form no part of the claimed design.

1 Claim, 7 Drawing Sheets
